US0D1049803S

(12) **United States Design Patent** (10) **Patent No.:** **US D1,049,803 S**
Ketterling (45) **Date of Patent:** **** Nov. 5, 2024**

(54) **DRIVER FOR ROTARY SOD CUTTING TOOL**

(71) Applicant: **Kody J. Ketterling**, Twin Falls, ID (US)

(72) Inventor: **Kody J. Ketterling**, Twin Falls, ID (US)

(**) Term: **15 Years**

(21) Appl. No.: **29/831,180**

(22) Filed: **Mar. 17, 2022**

Related U.S. Application Data

(63) Continuation-in-part of application No. 17/080,790, filed on Oct. 26, 2020.

(57) **CLAIM**

The ornamental design for a driver for rotary sod cutting tool as shown and described.

DESCRIPTION

FIG. 1 is a perspective view of a driver for rotary sod cutting tool, showing my new design.

FIG. 2 is a front view thereof.

FIG. 3 is a side view thereof, rotated 60 degrees, respective to the front view.

FIG. 4 is a top view thereof; and,

FIG. 5 is a bottom view thereof.

1 Claim, 3 Drawing Sheets
